HEADLIGHT INDICATOR

Archie E. Benson, Miles City, Mont.

Application April 22, 1937, Serial No. 138,459

7 Claims. (CL 240—8.4)

This invention relates to improvements in headlight indicators.

The object of this invention is to provide a device that will indicate to the driver of a vehicle when his headlights are working; that will be constructed so that light from an approaching vehicle will not affect the indicator; and that will be positioned so that the driver can see at a glance without removing his eyes from the road whether both headlights are properly functioning.

Other objects and advantages of the invention will become apparent from the specification of which the drawing forms a part, and wherein:

Figure 1 is an elevational view of the device applied to the radiator cap of an automobile.

Figure 2 is a vertical sectional view on the line 2—2 of Figure 3.

Figure 3 is a horizontal sectional view on the line 3—3 of Figure 1, and

Figure 4 is a cross-sectional view on the line 4—4 of Figure 1.

Referring more particularly to the drawing wherein like reference characters designate like or corresponding parts in the different views, a vehicle radiator is shown at 10 and is provided with a radiator cap 11 to which is secured a supporting arm 12 by means of bolts 13.

A cone shaped casing 14 is provided with a horizontal partition 15 and a vertical partition 16 extending downwardly from partition 15. The casing 14 has a pointed closed end 17 and an open end 18. A socket 19, formed integral with partitions 15 and 16, and adjacent the open end 18, is threaded to receive the threaded end 20 of arm 12 to mount casing 14.

The members 21 which are bent upon themselves at 22 are mounted in partition 15 and have their opposite ends 23 and 24 extending toward the open end 18 of casing 14. The lower and larger ends 23 of members 21 are bent outwardly to position them to receive the light rays from the headlights (not shown) of the vehicle. End 18 of casing 14 is provided with enlarged portions 25 which are flared outwardly as seen in Figure 4 to prevent them obstructing the rays from the headlights to openings 23 and also to assist in shielding openings 23 from light from approaching vehicles.

Members 21 are composed of a light transmitting substance such as glass which may be colored, and are cylindrical in shape tapering from their enlarged ends 23 to their restricted ends 24.

For operation the device is mounted as shown in Figure 1. The rays from each headlight will be transmitted through the member 21 mounted in the side of casing 14 nearest to that light. The

vertical partition 16 will shield the member 21 from light from the lamp most remote thereto. Thus if one light is not ignited there is no possibility of the other light causing a reflection through both indicators 21. The horizontal partition 15 tends to keep the upper part of casing 14 dark so that the glow emitted from ends 24 will be clearly visible. The members 21 are mounted as far to the rear of casing 14 as possible without obstructing the rays from the headlight corresponding thereto, so that ends 23 will be shielded from practically all other sources of light.

It is to be understood that only the preferred embodiment of the invention has been shown the right being reserved to make such changes in the construction and shape of the parts as will not depart from the spirit and scope of the invention as claimed.

I claim as my invention:

1. A headlight indicator comprising a casing 20 provided with a horizontal partition and a vertical partition extending downwardly therefrom, one end of said casing being open, and light transmitting members mounted in said horizontal partition and having their ends extending toward the 25 open end of said casing.

2. A headlight indicator comprising a cone shaped casing provided with a horizontal and vertical partition, horn shaped members mounted in said casing and being bent upon themselves, the 30 ends of said members extending toward the open end of said casing, and one end of each member being positioned to receive rays from a headlight.

3. A device of the class described comprising a hollow cone shaped casing provided with a horizontal and vertical partition, translucent members bent upon themselves and mounted in said horizontal partition and on each side of said vertical partition, and with their ends extending toward the open end of the casing, and one end of each 40 member being positioned to receive rays from a headlight whereby the members are illuminated.

4. A headlight indicator comprising a casing open at one end and adapted to be mounted between and in front of a pair of vehicle headlights, 45 and horn shaped light transmitting members mounted in said casing, said members being bent upon themselves with their opposite ends extending toward the open end of said casing to receive light rays through corresponding ends of said 50 members to illuminate the opposite ends.

5. A device as in claim 4, said first mentioned ends being bent to extend away from each other whereby each will face toward one of said headlights.

6. A headlight indicator comprising a casing open at one end and adapted to be positioned between and in front of a pair of vehicle headlights, and light transmitting members mounted in said casing, said members being bent upon themselves and having their opposite ends extending toward the open end of the casing, the members having corresponding ends extending away from each other, said ends each facing a headlight

to receive the rays therefrom to illuminate the opposite ends.

7. A device as in claim 6, said casing having a horizontal partition in which said light transmitting members are mounted and a depending shield disposed between the diverging ends of said members. 5

ARCHIE E. BENSON.
